Filed Jan. 17, 1966, Ser. No. 648

Term of patent 14 years

(Cl. D13—1)

FIG. 1

FIG. 2

FIG. 3

FIG. 5

FIG. 4

FIG. 1 is a front elevational view of a sheathing strip showing my new design;

FIG. 2 is a view of the bottom edge of the sheathing strip of FIG. 1;

FIG. 3 is a rear elevational view of the sheathing strip of FIG. 1;

FIG. 4 is a perspective view of a portion of the sheathing strip shown in FIGS. 1-3; and

FIG. 5 is an enlarged side elevational view of the sheathing strip shown in FIG. 1.

The characteristic feature of my design resides in the horizontal groove, bounded by smooth arcuate bends, in the lower portion of the face of the sheathing strip.

I claim:

The ornamental design for a sheathing strip, substantially as shown and described.
